UNITED STATES PATENT OFFICE.

JOHN H. COLLIER, OF ELSIE, MICHIGAN.

MUSIC-TURNER.

No. 901,421.

Specification of Letters Patent.

Patented Oct. 20, 1908.

Application filed June 2, 1908. Serial No. 319,860.

To all whom it may concern:

Be it known that I, JOHN H. COLLIER, a citizen of the United States of America, residing at Elsie, in the county of Clinton and

5 State of Michigan, have invented certain new and useful Improvements in Music-Turners, of which the following is a specification, reference being had therein to the accompanying drawings.

10 The invention relates to music turners, and consists in certain novel features in the construction as hereinafter set forth.

In the drawings, Figure 1 is a perspective view; Fig. 2 is a vertical longitudinal section on line $x-x$; Fig. 3; Fig. 4 is a horizontal section through the base; Fig. 5 is a perspective view of the clip; Fig. 6 is a horizontal section through the standard on line $y-y$; Fig. 2, Fig. 6 is a perspective view 20 of one of the shafts showing the construction thereof.

A is a base provided with a series of horizontally extending shelves, or guides B.

C is a tubular standard rising centrally 25 from the base A and inclosing a nest of tubular shafts D. These shafts extend down into the base to the various partitions B, the smallest shaft extending lowest and at the upper end of the standard the shafts are 30 stepped in inverse order.

To each of the shafts D is secured, at opposite ends, a pair of laterally projecting arms E and E', the lowest arms E' extending between the horizontal shelves B. Each 35 pair of arms E and E' constitute a leaf support for the music, and by a rotation of its shaft, this leaf support may be turned from a position at the right of the standard to a corresponding position at the left thereof, or 40 the reverse movement.

For rotating the shaft, each has secured thereto at its lower end intermediate the shelves B a disk, or pulley F, preferably formed integral with the arm E', and to 45 each of these disks is attached a flexible band G, preferably of spring metal, which passes around an idler pulley H, and thence outward toward the end of the base. I are

50 springs attached to the bands G, the tension of which may be adjusted by threaded shank J passing through the end of the base and engaged by adjusting nuts K. Thus, when the spring is under tension, it will draw upon the band, and tend to rotate the 55 disk F and shaft attached thereto to turn the leaf holder from right to left.

Each of the disks F is normally engaged by a locking dog L, which engages a notch a in the periphery of the disk. The dog is pressed into engagement with the notch by 60 suitable means, such as the spring M, and is withdrawn from engagement by the operation of a key, or lever N, there being a number of said keys corresponding to the number of dogs and disks. As shown, each of 65 the keys N is in the form of a bell crank lever pivoted in the base, and having the upturned arm b engaging an actuating arm e of the dog L, which latter is pivoted at d to the base. 70

For securing the leaves of the music to the pairs of arms constituting the leaf holder, I preferably employ a construction which supports the outer edge of the leaf as well as at top and bottom. For this purpose clips O 75 are attached to the bars O', connecting the outer ends of the arms E and E'. Each clip comprises a plate O² for passing beneath the under side of the music leaf and a clamping jaw O³ under tension of a spring O⁴. The 80 rear plate O² is preferably of considerable length so as not only to support the music sheet at the center, but also extends a sufficient distance towards the ends to support the corners. In addition to these clips O 85 clips P are attached to the upper and lower arms E and E' for engaging the adjacent edges of the music sheet.

I preferably provide adjustment by which the spacing beneath the upper and lower 90 arms may be changed for music sheets of different height. This is accomplished by forming the standard C in two parts e and f telescopically engaging each other and clamped for different positions of adjustment, as by the clamping holder g. The tubular shafts D are also formed in sections, which slidably engage each other, and as shown, the sections are halved in cross section, as illustrated in Fig. 5 and Fig. 6. 100 Thus, when the casing C is adjusted to alter its length, a corresponding adjustment in the length of shafts D is effected automatically.

The base A is preferably made in two sections, hinged to each other and adjustable, so as to tilt the standard C to different angles, as illustrated in Fig. 3. 105

To permit of adjustment in height of the music holder, the bars O', which support the 110 clips O, are preferably formed in two sections, which telescopically engage a tubular

bearing O^o on the clip being held in said bearing by friction.

To adapt the leaf supports for holding music of varying widths, the outer clips P are preferably adjustable towards and from the axis of the rock shafts. This is preferably accomplished by forming the arms E and E' of telescopic sections E^o and E^o which may be adjusted to vary the distance of the rod O' from the standard.

What I claim as my invention is:

1. In a music turner, the combination with a tubular casing, of a plurality of concentric shafts nested within said casing and extending out therefrom at opposite ends, arms secured to the opposite ends of said shafts, and projecting laterally therefrom, and connections between said arms for forming an intermediate support to the music sheet.
2. In a music turner, a plurality of concentric nested shafts, arms secured to the opposite ends of said shafts, and projecting laterally therefrom, and means whereby said shafts may be extended and contracted in length to vary the distance between said arms.
3. In a music turner the combination with an extensible tubular casing, of a plurality of concentric shafts nested therein, each shaft being formed in two sections longitudinally slideable or rotatively locked to each other, and arms secured to the opposite ends of said shafts and projecting laterally therefrom.
4. In a music turner the combination with a tubular casing, of a plurality of concentric shafts nested therein, and projecting outward from the opposite ends thereof, disks secured to the several shafts at the lower end of said casing, flexible connections peripherally wrapped about said disk and extending laterally therefrom, springs connected to said flexible connections for placing a tension thereon, arms secured to opposite ends of said shafts and projecting laterally therefrom; and dogs for engaging said disks to hold the same from rotation.
5. In a music turner, the combination with a shaft having a pair of parallel arms mounted thereon, of a rod extending between the outer ends of said arms and a clip attached to said rod for engaging the center of the outer edge of the music sheet, said clips comprising complementary plates and one of said plates being relatively long, for the purpose described.
6. In a music turner, the combination with

a plurality of concentric nested shafts, having the inner shaft projecting beyond the outer, to form steps, disks mounted on the steps of said shafts, flexible bands secured to said disks and wrapped peripherally about the same; tension device for drawing said bands tangentially from said disks, dogs engaging notches in said disks and a series of finger levers respectively engaging said dogs whereby those may be successively released from said disks.

7. In a music turner, the combination of a hollow base, having a series of shelves, or partitions therein, a plurality of concentric nested shafts extending into said hollow base and stepped to bear against the several shelves, disks mounted upon said shafts between said shelves, flexible bands connected to said disks, and extended peripherally about the same, tension device for said bands, dogs for engaging notches in said disks between said shelves, and finger levers projecting out from said hollow base and respectively engaging said dogs whereby they may be individually released from the disks.

8. In a music turner, the combination of an adjustable rock shaft, a pair of parallel arms secured thereto and adjustable toward or from each other, a clip for engaging the outer edge of the music sheet intermediate said arms and adjustable thereon, and a telescopic rod connecting said arms and supporting said clip.

9. In a music turner, the combination with a plurality of leaf supports, spring actuated rock shafts for actuating said supports, and a trip mechanism for successively releasing said rock shafts, of a base upon which the said mechanism is mounted, a sub base to which said base is hinged, and means for adjusting said base upon said sub base for changing the angularity of the leaf supports.

10. In a device of the class described, the combination of a holder, a plurality of upright shafts adapted to be lengthened or shortened, an arm on the upper end of each shaft, and an adjustable clasp movable longitudinally on each arm.

In testimony whereof I affix my signature in presence of two witnesses.

JOHN H. COLLIER.
